COMBINED CHILD'S BED, CLOTHES PRESS, AND CHEST

Claude Jackson, Cincinnati, Ohio, assignor to Stanley Adamchels, Springfield, Mass.

Application January 15, 1952, Serial No. 18,074

Term of patent 14 years

(Cl. D33—19)

To all whom it may concern:

Be it known that I, Claude Jackson, a citizen of the United States and a resident of Cincinnati, in the county of Hamilton and the State of Ohio, have invented a new, original, and ornamental Design for a Combined Child's Bed, Clothes Press, and Chest, of which the following is a specification, reference being made to the accompanying drawing, forming a part thereof.

Fig. 1 is a perspective view of a combined child's bed, clothes press and chest showing my new design.

Fig. 2 is a side elevational view thereof.

Fig. 3 is a top plan view.

Fig. 4 is a front elevational view; and

Fig. 5 is a rear elevational view.

I claim:

The ornamental design for a combined child's bed, clothes press, and chest, substantially as shown.

CLAUDE JACKSON.
